(57) **CLAIM**

The ornamental design for wearable smart headphones, as shown and described.

DESCRIPTION

FIG. 1 is a perspective bottom view of a wearable smart headphones according to the present invention;

FIG. 2 is a perspective back view of the wearable smart headphones of FIG. 1;

FIG. 3 is a perspective front view of the wearable smart headphones of FIG. 1;

FIG. 4 is a perspective side view of the wearable smart headphones of FIG. 1;

FIG. 5 is a perspective top view of the wearable smart headphones of FIG. 1;

FIG. 6 is a side view of the wearable smart headphones of FIG. 1; and,

FIG. 7 is a top view of the wearable smart headphones of FIG. 1.

The broken lines depict portions of the wearable smart headphones that form no part of the claimed design.
